PAGE 2

Fig. 2

Fig. 3.

FIG. 1 is a front perspective view taken from the top and one side of a heated food display case embodying my new design;

FIG. 2 is a rear perspective view thereof; and

FIG. 3 is a side perspective view partially in elevation of the side opposite that shown in FIG. 1.

The application is a continuation-in-part of my co-pending application, Serial D. 50,662, filed April 29, 1958, entitled Heated Food Display Case, now abandoned.

I claim:

The ornamental design for a heated food display case, as shown and described.
